R. E. McFARLANE

CAR DOOR

Filed Sept. 7, 1920

FIG. 3.

FIG. 1.

FIG. 2.

FIG. 4.

Inventor
ROBERT E. McFARLANE,

By

Edward E. Clement

UNITED STATES PATENT OFFICE.

ROBERT E. McFARLANE, OF DULUTH, MINNESOTA.

CAR DOOR.

Application filed September 7, 1920. Serial No. 408,727.

To all whom it may concern:

Be it known that I, ROBERT E. McFARLANE, a citizen of the United States, residing at Duluth, in the county of St. Louis and State of Minnesota, have invented a certain new and useful Improvement in Car Doors, of which the following is a specification.

My invention relates to railroad car doors, and has for its object the improvement of such doors to better adapt them for retaining grain and similar material. The invention is in the nature of an improvement on that described in the U. S. patent granted April 1, 1919, to H. D. Ehle, No. 1,299,312.

The features of improvement in this present invention are the following: 1st, the door is made of a double thickness of one inch boards or more, reinforced on the outside with metal plates, said plates being secured with countersunk rivets passing through inner plates and with the rivet heads on the inside, leaving the outer face of metal reinforcing plates flush; 2d, a metal angle plate is provided on the bottom of the door on the outside, extending under the door to hold the canvas strip described in the said patent; this plate is riveted through the door with countersunk rivets with light plate washers under the rivet heads, and is secured to the bottom edge of the door with countersunk wood screws; 3d the outer face of the same angle plate is made with three oblong slots for engagement of a pinch or crow bar, for raising the door from outside of car, the angle under the edge of the door protecting the same and the fabric from damage by the pinch bar; 4th, the door is given an upper hinged section which can be used to load to a higher level, if required, than is possible with the door of the patent; 5th, locking devices are provided for the door when closed, consisting of two pivoted dogs, mounted on the right and left door jambs respectively, the said jambs being faced with metal plates having oblong slots to receive angle pieces riveted to the dogs, which are of spring steel to allow the projecting angles to be sprung back into the slots when the dogs are out of service; 6th and last, a pivoted steel spring angle bar is placed on the inside of the car in such position that when swung around its pivot its longer end will engage the inner edge of the door when closed, and when the door is raised for opening, the bar will rise with it,

and when the door is open the bar can be swung back clear of the opening in the side of the car.

My invention is illustrated in the accompanying drawing, in which Figure 1 is an inside view of the side of the car with door closed; Figure 2 is a horizontal section of same taken above the door; Figure 3 is a vertical section through the door, drawn on an enlarged scale; and Figure 4 is an outside view of a part of the door showing the bottom angle piece.

Referring to the drawings, and especially to Figure 1, it will be seen that I pivot my door by means of an L shaped slot 13 working on a pivot bolt 14, and when the door has been raised and swung back away from the opening 2, I detain it by means of a metal spring clip holder 18 mounted on a strip (or angle if desired) 17, the door resting on a block 16, all as in the patent.

The improvement features are shown as follows: The door 3 has an upper section 22 hinged at 23 24 to open inwardly. The sides 80 are faced with metal strips or plates 4 and 5 on the inside as in Patent 1,299,312 above referred to and 11 on the outside, all riveted as stated, with the outer ends of the rivets flush; and the bottom of the door is fitted 85 with an angle plate of metal, 6, (Figs. 1, 3 and 4,) having slots 60, (Fig. 4) to receive the end of a pinch bar, 25, (Fig. 3), the lower edge of the door and the canvas under it being thus protected from injury. The 90 jambs of the opening 2, right and left, are fitted with metal plates 9, each carrying a pivoted dog 7 or 8, which when down engage the upper edge of the door to lock it singly against the jambs. Further locking 95 for the lower part of the door is provided by the pivoted steel spring angle bar 19 having a long end and a short end, the former engaging the metal strip 5 when the door is closed, but swinging around on the 100 dotted line and remaining clear of the opening 2 when the door is stowed. Each dog 7 or 8 carries on its back an angle piece 10 which when the dog is in service can engage the edge of the jamb and hold the 105 dog against displacement, and when the dog is retracted can be sprung into the slot 100 in the jamb plate to hold the dog in inoperative position. The lower angle plate 6 extends under the canvas or fabric strip 110 27, (Fig. 3) and beside protecting the same and the edge of the door from injury by

the pinch bar, also takes all wear in closing the door. The slots 60 for engagement of the pinch bar are shown in Fig. 4.

It is to be understood that while I have specifically described the best form known to me of my invention, I contemplate some latitude in construction. For example, the dogs 7 and 8, instead of being of spring metal, may be made of stiff metal and given other means to permit yielding in locking and unlocking. The claims are to be construed to cover all proper equivalents for the specific forms set forth, therefore.

Having thus described my invention, what I claim is:

1. A car door comprising a body adapted to slide across the inner face of the door opening, built up of two layers of wood strips laid so as to break joint and make a solid mass, inner and outer metal facing strips along the vertical edges of said body, rivets connecting said metal strips through the wooden body, a strip of canvas extending across the lower edge of the door and projecting inwardly therefrom, and a metal angle plate covering and protecting said canvas between it and the bottom of the door and having its flange extending vertically upward across the outer face of the

door with openings or recesses in said flange to receive a pinch bar or similar means for raising the door.

2. In combination with a car door of the type claimed in claim 1 a pair of metal latch members pivoted on metal plates on the side jambs of the door opening, and extending over the top of the door when closed so as to engage the inner metal facing strips, whereby all bearing and locking surfaces are of metal.

3. In combination with a car door of the type claimed in claim 2, a metal locking plate on each jamb of the door opening, a spring metal dog thereon having a terminal hook adapted to engage the upper and inner metal edge plate of the door when closed, to lock the same, and an angle piece or shoulder carried by the dog adapted to snap over the edge of the door jamb plate to lock the dog when in engagement with the door.

4. The combination claimed in claim 3, with the additional element of an opening in each door jamb plate adapted to receive the shoulder on the dog when retracted and thereby hold the same out of locking position.

In testimony whereof I affix my signature.
ROBERT E. McFARLANE.
